UNITED STATES PATENT OFFICE

2,488,110

ELECTRICAL TIME SWITCH

William J. Aitken, Manitowoc, Wis.

Application April 30, 1948, Serial No. 24,242

5 Claims. (Cl. 200—38)

1

There are various kinds of motor-driven automatic switches adapted to open and close electric circuits at predetermined times during a predetermined period of time, say each twenty-four hour day; the cycle being repeated as long as the operating motor continues to run.

The present invention has for its object to produce a switch of the aforesaid general type that shall be simple and novel in construction, that shall be highly efficient and reliable in operation over long periods of time without needing attention and that can very easily and quickly be adjusted to achieve any desired timing cycles.

Another object of the invention is to provide an automatic electric timing device including a synchronous-electric-motor-driven timing mechanism comprising a plurality of tripper-arm-actuated triangular timing wheels cooperating with a pair of coaxially mounted switch actuating cams; the cams and switches being so constructed and so arranged that the circuit controlled by said switches is closed and opened at predetermined intervals of time with snap action to thereby obviate arcing between the switch contacts.

Another object of the invention is found in the provision of manually operable means permitting manual operation of the switches into either closed or open position at any desired time without altering any automatic preset sequence of switch operation.

Another object of the invention resides in the provision of novel means for latching the switch-actuating tripper arms to a time-graduated dial plate which is driven by a synchronous electric motor including a novel frictional mounting for the pivotal ends of the tripper arms whereby the tripper arms may readily be manually adjusted relatively to one another and to the dial plate without disconnecting the dial plate from its operative connection with the motor.

The various features of novelty whereby the present invention is characterized will hereinafter be pointed out with particularity in the claims, but, for a full understanding of the invention and of its objects and advantages, reference may be had to the following detailed description taken in connection with the accompanying drawings, wherein:

Fig. 1 is a front view of a switch embodying my invention in a preferred form, removed from its casing; Fig. 2 is a side view of the switch viewed from a point to the right of Fig. 1; Fig. 3 is a rear view of the switch; Fig. 4 is a section on line 4—4 of Fig. 2 showing the indexing device; Fig. 5 is a section on line 5—5 of Fig. 4; Fig. 6 is a section

2

on line 6—6 of Fig. 2, only the cam shaft and the tripper-arm-actuated triangular timing wheels thereon being shown; Fig. 7 is a section on line 7—7 of Fig. 1, only the cam shaft and the parts contiguous thereto being shown; Fig. 8 is a view of the rear or underside of the dial unit; Fig. 9 is a view of the switch operating mechanism looking at the opposite side of the switch from that which is presented to the observer in Fig. 2; Fig. 10 is a section on line 10—10 of Fig. 9; and Figs. 11 and 12 are sections on an enlarged scale taken, respectively, on lines 11—11 and 12—12 of Fig. 1.

Referring to the drawings, 15 is a plate composed of tough insulating material, which may be of the phenolic resin type. On the rear side of this plate is an electric motor 16 provided with a dust-proof gear casing 17 that fits snugly against and is fastened to the plate 15. Also on the rear side of the plate 15 are a plurality of terminals, 18, 19, 20 and 21, being shown; these terminals being arranged at one end of the plate and projecting beyond the same. The motor is connected directly to terminals 18 and 19 so that, whenever these two terminals are connected to an energized outside circuit, the motor runs. Terminals 20 and 21 are for connection with the translating device that is to be energized intermittently; and, in order alternately to connect and disconnect terminals 20 and 21 to terminals 18 and 19, I provide two switches 25 and 26.

Switch 25 comprises a contact piece 27 on terminal 18 and a cooperating contact piece 28 fixed on one end of a spring arm or blade 29, while the other end of such arm or blade is anchored to terminal 26. Switch 26 comprises a contact piece 30 mounted on terminal 19 and a second, cooperating contact piece 31 on a spring arm or blade 32 that is anchored to terminal 21. The terminals are L-shaped, their shorter arms 18^a, 19^a, 20^a, and 21^a projecting rearwardly from and at right angles to plate 15; arms 18^a and 20^a being longer than the other two, so that switch 25 is farther away from the supporting plate than is switch 26.

The means for operating the switches is a cam shaft 34 mounted on plate 15 not far from the contact-bearing ends of the switch members; the shaft extending through the plate at right angles thereto and projecting forwardly and rearwardly therefrom. Fixed to the rearwardly projecting part of the cam shaft, in the same planes parallel to the supporting plate that contain the longitudinal center lines of switch arms 29 and 32, respectively, are two switch-actuating cams 35 and 36 composed of suitable insulating material. These two cams are alike, each being pref-

erably shown in the form of a pair of thick discs having a plurality of excisions in its edge, obviously each cam could comprise a single disc of thick insulating material. Because I have selected for the sake of illustration a timer that opens and closes a circuit at least three times, during each revolution of the cam shaft 34, each cam has three V-shaped excisions; one side 37 of each excision being approximately radial while the other side 38 makes an obtuse angle therewith. The excisions in the two cams register with each other axially of the cam shaft.

Switch arm 29 has thereon a finger 39 that lies in the plane of and reaches over to cam 35. Arm or blade 32 has at its free end an extension 40 constituting a finger that extends into proximity to cam 36. The parts are so proportioned that these two fingers at all times occupy similar positions relatively to the corresponding cams. Also, each switch arm is constantly under stress so that the contact piece thereon is firmly pressed against the cooperating stationary contact, when not restrained by its actuating cam.

As will hereinafter be explained, the cam shaft 34 is driven step by step in the counter-clockwise direction as viewed in Fig. 3. When the fingers are riding on the unmutilated portions of the cams, as in Fig. 3, the switches are open. Then, upon turning the cam shaft until the nearest excisions in the cams reach the fingers, the fingers drop abruptly into those excisions and both switches close with a snap action. The excisions are so long and so deep that the switches may thereafter open with a snap action, even though the fingers 39 and 40 are required to ride up a gradual slope. This is for the reason that whenever the cam shaft has been turned half way through an angular distance of 60° , it is driven sharply the rest of the way by a powerful indexing device.

The indexing device, as best shown in Figs. 4 and 5, comprises a six pointed star wheel 41, fixed to the cam shaft in front of and near plate 15. Cooperating with this wheel is a plunger 42 that has a wedge-shaped end 43 that fits into the V-shaped recess between any two consecutive points on the wheel. The plunger is provided with a stem 44 mounted in a suitable bracket 45, fixed to plate 15, for sliding movements radially of the cam shaft. A spring 46, surrounding the stem and bearing at one end against the plunger proper and at its other end against a part of the bracket, presses the plunger strongly against the star wheel. With the parts in the positions occupied by them in Fig. 4, a turning movement of the cam shaft results in forcing the plunger out of the recess in which it is seated. When the tip of one of the star wheel points reaches and passes a little beyond the sharp edge of the wedge, the spring rapidly forces the wedge against the trailing edge of that star wheel point and sharply drives the star wheel ahead.

The cam shaft is given a turning impetus at predetermined intervals by means driven by motor 16 and acting through two triangular timing wheels fixed to that part of the cam shaft that projects forwardly from the supporting plate 15. These timing wheels consist of a triangular metal plate 48 and a somewhat larger triangular plate 49. These timing wheels 48 and 49 are fixed to the cam shaft 34 in spaced relation to each other, with the larger wheel 49 disposed nearer to the supporting plate; the timing wheels being displaced 60° angularly of the shaft relatively to each other. Each edge of the timing wheel 48

contains a small depression 50, so located that there is a single depression at each apex or tip. At each tip of the timing wheel 49 is a little finger or projecting tip 51. On the outer end of the cam shaft 34 is a knob 52 which may be used for manually turning the shaft 34, whereas the inner end of the shaft 34 extends through a stationary bearing element 53 for the purpose of steadyng the shaft 34.

The actuator or means for actuating the switches through the cam shaft 34 and its co-operating timing wheels 48 and 49 includes elements carried by a motor driven circular dial 54; these elements being adjustable on the dial independently of each other. I prefer to employ as such elements arms which are pivotally mounted on and disposed radially of the dial; each arm having thereon a pin adapted to engage one of the timing wheels once during each revolution of the dial 54. A satisfactory arrangement is one having two arms, one to close and the other to open the switches, but a greater number may be used when desired.

In the arrangement shown, as best seen in Fig. 10, a shaft 55, driven by the motor 16, extends forwardly through supporting plate 15 and there terminates in a screw-threaded section 56. A nut 57 is screwed down as far as it will go on the shaft. Overlying this nut 57 is a detachable unit comprising the dial 54 and the two cooperating arms 58 and 59. These three members are fastened together by means of a device in the nature of a tubular rivet adapted to be slipped over the threaded end of the shaft. This fastening device comprises a disc-like head 60; a stem portion 61 of somewhat smaller diameter and of a length substantially equal to the combined thicknesses of the arms; and a short stem continuation 62 of still smaller diameter. The arms contain holes for the reception of part 61 of the fastener, while the dial has a central hole just large enough to receive the part 62 while resting on the shoulder at the juncture of parts 61 and 62 with each other. When the end of part 62 is headed over, as shown, the arms 58 and 59 and the dial 54 are frictionally fastened together without clamping the arms so tightly that they cannot easily be manually adjusted relatively to each other and to the dial. After the unit just described is slipped onto the screw-threaded section of the shaft 55 it then may be secured in place by means of a nut 63 screwed onto the shaft 55, thus fastening the dial 54 to the shaft 55 in a manner to compel it to rotate with the same but still permitting adjustment of the arms 58 and 59 relatively to each other and to the dial 54.

Each of the arms 58 and 59 projects somewhat beyond the periphery of the dial 54 and is there blanked and formed to provide first, little prongs respectively 64 and 65 that are bent over the edge of the dial and inwardly close to the dial face to limit the inward movements of the arms when moved into unlatched positions; and, second, little finger pieces with pointers respectively 66 and 67 that extend outwardly well beyond the periphery of the dial 54 and with their pointers 66 and 67 pointing toward suitable time-designating indicia or graduations arranged circularly and near the periphery of the dial.

The dial contains small holes 68, arranged in a circle having a diameter only a little less than that of the dial; thus bringing these holes close to the edge of the dial. When the dial is graduated over a period of twenty-four hours as shown,

the distance between the graduations of consecutive holes may conveniently represent fifteen minutes. Any other desired time designating indicia or graduations may be used to fit any desired operating conditions.

The arms 58 and 59 are latched in their positions of adjustment by pins thereon that enter the small holes 68 in the dial. When making the blanks for the arms each is provided with a hole 69 that is adapted to register consecutively with the small holes 68 in the dial as the arm is turned. Another hole 70 is also formed in each of the finger piece portions respectively 66 and 67.

In making up arm 58, a headed pin 71 is pressed into hole 69, as shown in Fig. 11, from the underside, and is caused to project far enough on the side next to the dial to permit it to enter any one of the holes 68 in the dial with which it may register. The arms are made of spring metal and tend constantly to lie flat against the dial. A heavier pin 72 has a reduced end which extends through hole 70 and is riveted to arm 58; this pin being the medium through which arm 58 actuates the timing wheel 48, as will further be explained. In making up arm 59, a pin 73 similar to pin 72, but much longer and having at one end a section 74 of small diameter, is securely driven into the hole 69 of arm 59 and is used to serve the functions of both pins 71 and 72; part 74 being adapted to extend up through any one of the holes 68 for the purpose of interlocking the arm 59 with the dial. The hole 70 in arm 59 is not used.

It will be understood that the parts are so proportioned and arranged that the cam shaft 34, shaft 55 that carries the dial, and pins 71, 72 and 73 are all parallel to each other, pin 72 being adapted to securely engage within depression 50 with what may be termed one tooth of the small timing wheel 48 whenever that pin is carried around to about a plane containing the axes of both of these shafts, while the switches are open and such tooth is the one nearest the dial as in Fig. 1. Pin 72 is too short, however, to engage the large timing wheel 49. Pin 73 is too close to the axis of rotation of the dial to engage timing wheel 48, but its length enables it to engage a tooth on the larger timing wheel 49 when the switches are closed and the cam shaft has been turned in the clockwise direction through an angle of 60° from the position that it occupies in Fig. 1.

In order that the dial may be used actually to indicate the time of day I provide a stationary pointer 75 in the form of a bracket mounted on the front side of the supporting plate 15 and extending beyond the plane of the dial and then laterally over the marginal portion of the face of the dial.

The operation of the apparatus has been to some extent explained along with the description of the structural features. Briefly stated, however, when the particular time switch apparatus shown is to be operated so as to close a circuit at a predetermined time of day and to open it again at a second predetermined time; the finger piece 66 and arm 58 is pressed back to unlatch the arm, which is then turned to bring the pointer 66 in registration with one of the holes 68 on the dial representing the hour at which the switches are to be closed and when the arm 58 is released its pin 71 will enter the hole 68 and latch the arm to the dial. The same procedure is followed with the circuit-opening arm 59 to set it at the hour

for again opening the switches; if the cam shaft is not already in one of its three "switch-open" positions such as shown in Fig. 1, knob 52 is turned in the clockwise direction until the switches are open; care being taken that the arms are so set that as the dial turns, the circuit-closing arm 58 moves up to the tripper-arm-actuated timing wheels ahead of circuit-opening arm 59.

After arm 58 has through the engagement of its pin 72 with the timing wheel 48 turned the cam shaft 34 through an angle of 30°, the indexing device is released into action and forcibly quickly rotates the shaft 34 through a further-like angle and holds it there. Now, however, one of the teeth on the larger timing wheel 49 lies in the path of the long pin 73 on arm 59 so that, at the proper time as the rotation of dial 54 is advanced, arm 59, acting on the larger timing wheel 49 will cause a rotation of the cam shaft 34 until the indexing device again acts to complete this particular step in the turning movement of the cam shaft; the snap action in this instance being important since, otherwise, the switches might open so slowly as to cause objectionable sparking.

It should be noted that the manually operable switch trip knob 52 permits manual operation of the switches at any time, if so desired, without altering any automatic preset sequence of switch operation.

While I have illustrated and described with particularity only a single preferred form of my invention, I do not desire to be limited to the exact details thus illustrated and described, but intend to cover all forms and arrangements that come with the definitions of my invention constituting the appended claims.

1. In an automatic electrical time switch, a switch having an arm movable to open and close a circuit, a rotatable shaft having thereon a cam adapted to engage said switch arm and move it, a pair of triangular timing wheels of different diameters fixed to said shaft in spaced relations lengthwise of the shaft, an actuator for said timing wheels rotatable about an axis parallel to said shaft and in a plane close to the plane of the smaller one of said timing wheels, two pins of relatively different lengths on the actuator paralleling said shaft, one of the pins being long enough to intersect the plane of the larger one of said timing wheels and the other being too short to reach that plane but long enough to intersect the plane of the smaller one of said timing wheels, the radial distances of the pins from the axis of the actuator being such that the short pin is adapted to operatively engage the smaller one of said timing wheels while the longer one of said pins reaches only to the larger one of said timing wheels.

2. In an automatic electrical time switch, a switch-operating cam shaft, a motor driven shaft parallel to the cam shaft and having thereon a time-designating dial disposed in a plane at right angles to the shafts, two timing wheels fixed to the cam shaft in planes paralleling that of the dial and spaced apart from each other, the timing wheel nearest the plane of the dial being smaller in diameter than the other, two pins adjustably mounted on the dial and paralleling said shafts, one pin being long enough to intersect the plane of the larger timing wheel and the other pin being only long enough to intersect the plane of the smaller timing wheel, and the long pin being at such a distance from the cam shaft, when nearest the same, that it cannot en-

gage the smaller timing wheel, whereas the short pin is so located that it can engage with said smaller timing wheel.

3. An automatic electrical time switch as set forth in claim 2, wherein said time wheels are of triangular form and are relatively displaced 60° with respect to each other, angularly of the cam shaft.

4. An automatic electrical time switch as set forth in claim 2, wherein each timing wheel is provided with the same number of pin-engaging projections, and wherein the timing wheels are so displaced angularly with respect to each other that the turning of each timing wheel by the corresponding pin places the other timing wheel in position to be engaged by the pin corresponding thereto.

5. An automatic electrical time switch as set forth in claim 2 having, in addition, an indexing

star wheel on the cam shaft, together with a spring-pressed wedge-shaped dog cooperating with said indexing wheel to snap it from one position to the next after one of the pins on the dial has rotated one of the timing wheels a predetermined angular distance.
